OR D 19,075

DESIGN.

G. E. WILBUR.

STOVE SHELF.

No. 19,075.

Patented Apr. 30, 1889.

UNITED STATES PATENT OFFICE.

GEORGE E. WILBUR, OF TAUNTON, MASSACHUSETTS, ASSIGNOR TO THE
WEIR STOVE COMPANY, OF SAME PLACE.

DESIGN FOR A STOVE-SHELF.

SPECIFICATION forming part of Design No. 19,075, dated April 30, 1889.

Application filed March 8, 1889. Serial No. 302,534. Term of patent 14 years.

To all whom it may concern:

Be it known that I, GEORGE E. WILBUR, a citizen of the United States, residing at Taunton, in the county of Bristol and State of Massachusetts, have invented and produced a new and original Design for Stove-Shelves for Cooking Stoves and Ranges, of which the following is a specification, reference being had to the accompanying photograph, forming part thereof.

The photograph is a representation of the stove-shelf in perspective.

The leading features of my design consist in a central panel formed in the box or central supporting-section of the shelf, having a plane oval formed by a border of projections, the greatest diameter of the oval being vertical, and radiating flame-like forms extending from said border and filling the remainder of the panel; also, the fan-shaped figures in the upper parts of the wings of said box; also, the finish of the edge of said wings by a scroll in part twisted; also, the central figure of the back piece of the shelf, which is like a portion of the panel above referred to; also, the finish of the edge of said back section.

A is the shelf-support; B, the shelf; C, the shelf-back.

The support A has a central section in the general shape of a box, and the side wings, a' a''. The box has the central panel, a³, comprising the oval center a⁴, formed by the small half-round knobs or projections a⁵, and the flame-like forms a⁶, radiating from the said border and filling the remainder of the panel. Upon each side of the box, where it joins the wings, is a vertical line of ornamental relief figures, b. Each of the wings has a fan-shaped figure, c, extending from the inner corner downwardly. The edge of each wing is finished by a scroll having the curved lower section, d', the line-work d'', following the edge of the wing, the twisted section d³, and the divided or separated upper end, d⁴. There is also upon each wing, near its base, a rosette or circular figure, d⁵.

The back plate of the stove-shelf has the

central figure comprising the plain lower center, e', the border of projections e², and the radial flame-like tongues or section e³, extending to the curved border e⁴. The edge of the back plate is finished by a scroll similar to that of the edge of the wings, and comprising the circular figures f, one at each end of the base, and the twisted sections f', and the plain-line connections f².

Having thus fully described my invention, I claim and desire to secure by Letters Patent of the United States—

1. The design for a stove-shelf for cooking stoves and ranges herein shown and described, comprising the box having a panel comprising an oval border and radial leaf or flame-like forms, the wings a' a'', having the fan-shaped figures c at each inner corner thereof, and the scroll edges, and the back plate having the scroll edge, and the central figure, e, having radial flame-like tongues or sections extending therefrom, as set forth.

2. In the design for a stove-shelf herein shown and described, the panel a³, comprising the radial flame-like tongues or sections extending from an oval center, as set forth.

3. In the design for a stove-shelf herein shown and described, the wings having the fan-shaped figures c, extending from the upper inner corners thereof and ornamented at their curved edges by the scroll, consisting of the twisted portion d', the line-work d'', and the separated upper part, d⁴, as set forth.

4. In the design for a stove-shelf herein shown and described, the ornamentation for the shelf-back C, consisting of the scroll at the upper edge thereof, comprising the figures f, the twisted sections f', and the plain-line connections f², and the central figure comprising the plain center e', the radial flame-like forms e³, and the curved border e⁴, as set forth.

GEO. E. WILBUR.
